ATTORNEY'S

UNITED STATES PATENT OFFICE.

MARTIN A. BARBER, OF CLEVELAND, OHIO, ASSIGNOR TO THE AMERICAN AUTOMATIC CONNECTOR COMPANY, OF WYOMING, DELAWARE, A CORPORATION OF DELAWARE.

LOCK FOR AUTOMATIC CONNECTERS.

Application filed November 10, 1923. Serial No. 674,087.

To all whom it may concern:

Be it known that I, MARTIN A. BARBER, a citizen of the United States, residing at Cleveland, in the county of Cuyahoga and State of Ohio, have invented a certain new and useful Improvement in a Lock for Automatic Connecters, of which the following is a full, clear, and exact description, reference being had to the accompanying drawings.

10 This invention relates to automatic train pipe connectors and is particularly concerned with the provision of means for insuring a close-fitting engagement between coupled connector heads.

15 Numerous devices for effecting an interlocking action between coupled heads have heretofore been used, one of which comprises a spring pressed plunger which is carried by one head and is arranged to engage a co-operating shoulder in a coacting head. The principal objection to a locking device of this character is the fact that the spring is apt to weaken after continued use, wherefore a positive locking action is not effected.

20 One of the objects of my invention, therefore, is the provision of a simple device which insures a positive locking action between coacting connector heads. Moreover, my invention contemplates the provision of 25 a durable device which may be readily attached to existing automatic connectors.

Further objects of my invention reside in 30 details of construction and combination of parts, all of which will be more clearly understood from the following description. The essential characteristics of my invention 35 will be summarized in the claims:

In the drawings, Fig. 1 is a side elevation 40 of a pair of coupled connector heads having my invention attached thereto; Fig. 2 is a front view of a connector head showing my invention in end elevation; Fig. 3 is a section taken on the line 3—3 in Fig. 2; and Fig. 4 is a fragmentary section on an enlarged scale 45 through a portion of a connector head.

My invention is adapted for use with various forms of connectors, but in the drawings I have illustrated it in connection with

a form of automatic connector having a spring pressed coupler head supported by 50 the draw bar of a train coupler and provided on one side with a projection and on the other side with a recess. This construction is indicated in the various figures wherein "A" indicates the draw bar of a railway car, 55 "B" the coupler thereof, and "C" the bracket depending from the draw bar and carrying the automatic connectors to which the train pipes are adapted to be attached.

The automatic connector illustrated comprises a head 10 having orifices at 11, 12 and 13 for receiving the air signal pipe, the air brake pipe and the steam pipe respectively. These orifices are arranged in a vertical line adjacent the center of the head and are positioned intermediate the projection 14 and recess 15. Each head is shown as having a shank 16 which has a sliding and universally movable connection with the bracket C, and as having a strong compression spring 17 70 surrounding the shank which presses the head away from the bracket so that in normally coupled position the springs are compressed.

My invention is concerned with the provision of a lock for receiving the connected heads in coupled position, and to this end I have shown it as embodied in a lock, which may be readily secured to each projection, and which is adapted to cooperate with a 75 shoulder in the recess with which the projection coacts. The preferred lock briefly comprises a spring-pressed plunger 23 within a casing 20 which is adapted to be attached to the lower end of a projection 14. The 80 plunger is arranged to engage a shoulder 32 which comprises the wall of an opening 33 in the coacting recess 15 when the heads are coupled, wherefore any non-axial force, such as increased pressure in the steam pipe, is 85 withstood by the locking device.

To insure a positive locking action of the plunger, I provide a relatively stationary member or ejector which is shown as a rigid bar 40, the rearward end of which is adapted 90 to be in threaded engagement with a

spring seat 41, and the forward end of which is adapted to be in sliding engagement with the top of the plunger. The forward end of the bar as at 42, is reduced in thickness 5 from the main portion of the bar, and is merged with the main portion by a conical ramp 43.

When the heads are in uncoupled position the adjustment of each head with relation 10 to the associated bracket is such that the reduced portion of the ejector is disposed intermediate the top of the plunger and the bottom of a cap 45. A spring 25 within the casing maintains the plunger in engagement 15 with the ejector. In this position the plunger is withdrawn into the casing.

The preferred connection between the ejector and the spring seat 21 is a threaded engagement as heretofore stated. To prevent 20 removal of the ejector by reason of the fact that the heads are subjected to a jarring action when the train is in motion, I prefer to make the ejector sufficiently long to project through opposed openings 46 and 25 47 respectively in the casing. The openings are sufficient in size to accommodate the main portion of the ejector.

To assemble a device made in accordance with my invention, the ejector is threaded 30 to the spring seat before the shank with the associated head is passed therethrough. While the head is thus removed, the casing, having a spring-pressed plunger therein, is rigidly secured to the head in such manner 35 that the openings 46 and 47 are adapted to be brought into alignment with the ejector when the shank is forced through the spring seat against the tension of the spring 17.

As heretofore explained, the reduced portion 40 of the ejector is disposed intermediate the cap and the plunger when the head is in normal extended position and the connector is uncoupled. When the head is moved backwardly during the normal coupling operation, then the casing is moved rearwardly with relation to the member 40 until the main portion of the ejector is disposed intermediate the plunger and the cap. In this position, the plunger is ejected from the casing and is in locking position. The ramp 43 on the ejector is so arranged that the plunger is ejected sufficiently for locking purposes, only after the locking shoulder thereof has passed beyond the locking shoulder 55 32 in the coacting recess.

A locking device made in accordance with my invention effects a positive ejection of the locking plunger while the heads are coupled. Moreover, the construction shown 60 permits the ejector to be readily attached to existing connectors, and enables the ejector to be maintained in operative position independently of the relative movement between the heads and the supporting bracket therefor.

Having thus described my invention, I claim:

1. In combination, an automatic connector head, a support therefor, a universal joint between the head and the support including 70 a spring seat, said head having a downwardly extending opening therein, a casing carried by the head adjacent the opening, a locking plunger slidably mounted within the casing, a spring associated with 75 the plunger and tending normally to hold the plunger within the casing, said casing having lateral aligned openings therein, and a rigid member carried by the spring seat and extending through said lateral openings, 80 said member having portions of different thickness in the region adjacent the casing, whereby movement of the head with reference to the support causes the member to enter the casing and permits the spring to withdraw the plunger into said casing.

2. In combination, an automatic connector head, a support therefor, a universal joint between the support and head including 90 a trunnion block mounted for rotation about a horizontal axis and a spring seat mounted for rotation about a vertical axis, a rigid member attached to the underside of the spring seat and projecting into said head, a casing carried by the head adjacent 95 the forward end of the member, said member comprising a round cam bar having the cam portion adjacent the casing and having the forward end portion smaller than the intermediate portion, and a spring within 100 the casing for urging the plunger into engagement with said member whereby the plunger is normally urged into unlocking position.

3. In combination, a pair of automatic 105 train pipe connector heads, each having a projection and a recess, the projection of one head coacting with the recess of a co-operating head, each recess having a shoulder adjacent the bottom thereof, and each head having a casing disposed opposite the shoulder, a plunger movable within each casing, a support for each head, a rigid member extending forwardly from each support and projecting through the 110 associated casing, yieldable means for normally urging the plunger into the casing, said member having such shape that the plunger may be urged by the spring into the casing when the heads are uncoupled, but is 115 ejected from the casing during the normal coupling operation.

4. In combination a pair of automatic 125 train pipe connector heads each having a projection and a recess, the projection of one head coacting with the recess of a co-operating head, a latch member in each head, an opening in the wall of the recess of each head into which the latch is adapted 130 to extend for locking the heads together,

a bracket supporting each head, a rigid member associated with each bracket and having a ramp thereon, a spring normally urging each latch into engagement with the member for normally tending to maintain the latch in unlocking position, said latch being adapted to enter the opening in the wall of the recess with which the associated

projection coacts when the ramp is brought into engagement with the latch, said engagement being effected upon movement of the heads with relation to the associated brackets. ¹⁰

In testimony whereof, I hereunto affix my signature.

MARTIN A. BARBER.
